[57] CLAIM

The ornamental design for a clasp for a rope halter, as shown and described.

DESCRIPTION

FIG. 1 is a left front perspective view of a clasp for a rope halter embodying my new design.

FIG. 2 is a side elevational view thereof, the opposite side being a mirror image of the side shown.

FIG. 3 is a front elevational view thereof.

FIG. 4 is a rear elevational view thereof.

FIG. 5 is a top plan view thereof.

FIG. 6 is a bottom plan view thereof.

FIG. 2

FIG. 1

FIG. 3

FIG. 4

FIG. 5

FIG. 6
